CLAIM

The ornamental design for an artificial fish attractor and escape habitat, as shown and described.

DESCRIPTION

FIG. 1 is an upper perspective view of an artificial fish attractor and escape habitat.

FIG. 2 is a lower perspective view of the artificial fish attractor and escape habitat of FIG. 1.

FIG. 3 is a front view of the artificial fish attractor and escape habitat of FIG. 1.

FIG. 4 is a rear view of the artificial fish attractor and escape habitat of FIG. 1.

FIG. 5 is a first side view of the artificial fish attractor and escape habitat of FIG. 1.

FIG. 6 is a second side view of the artificial fish attractor and escape habitat of FIG. 1.

FIG. 7 is a top view of the artificial fish attractor and escape habitat of FIG. 1; and,

FIG. 8 is a bottom view of the artificial fish attractor and escape habitat of FIG. 1.
